UNITED STATES PATENT OFFICE

HENRY O. DE H. SEGRAVE, OF LONDON, ENGLAND

DESIGN FOR AN AUTOMOBILE BODY

Application filed April 15, 1929. Serial No. 30,904. Term of patent 7 years.

To all whom it may concern:

Be it known that I, HENRY O. DE H. SEGRAVE, a subject of the King of England, residing at Ship House, 20 Buckingham Gate, London, S. W. 1, England, have invented a certain new, original, and ornamental Design for an Automobile Body, of which the following is a specification, reference being had to the accompanying drawing, forming a part hereof, in which—

Fig. 2 is a top plan view, and

Fig. 3 is a front elevation showing my new design.

I claim:

The ornamental design for an automobile body substantially as shown.

In testimony whereof, I affix my signature.

H. O. D. SEGRAVE.
